UNITED STATES PATENT OFFICE.

ANNA CLEVES, OF OMAHA, NEBRASKA.

ADJUSTABLE SKIRT-SUPPORTER.

No. 873,348.

Specification of Letters Patent.

Patented Dec. 10, 1907.

Application filed May 26, 1905. Serial No. 262,411.

To all whom it may concern:

Be it known that I, ANNA CLEVES, a citizen of the United States, and resident of Omaha, in the county of Douglas and State 5 of Nebraska, have invented a new and useful Improvement in Adjustable Skirt-Supporters.

In the accompanying drawing, I have shown in Figure 1, a view with portion removed of a skirt supporter embodying my 10 invention. Fig. 2 shows an edge view of one of the supporting members.

It is well known that it is at times difficult to properly secure a skirt to a waist.

15 The aim of my invention is to provide a skirt supporter so arranged that the waist and skirt may be secured, the supporter being further adapted to receive a broad or narrow band, belt, or ribbon to cover and hide 20 the union of the waist and skirt.

In carrying out my invention, I provide two similar members A, and B, preferably of sheet metal or other suitable material so arranged that these members may be pivotally 25 adjusted. The member A, has its ends a, bent so as to extend at right angles, as is shown in the figures, the ends terminating in the ears a. Secured to the rear curved ends a, are the projecting ears 3, which ears are 30 adapted to work over the ordinary eyes 2, to hold the belt in position. The eyes 2, are provided with the attaching loops 1, which are secured to the skirt as shown. The member B, is also provided with such projecting 35 ears 3, under which the eyes 2, work as shown. Near the upper recurved end, the members A, and B, are provided with the eyes 4, while secured to the belt x, are the hooks 5, adapted to hook over the end 4, as is shown

in Fig. 1, so that the belt is secured to the 40 skirt supporting member A and B. From this it will be seen that the skirt z, is provided with the eyes 2, under which the lower ears of the members A, and B, are inserted, while the belt is inserted between the members A, 45 and B, and the recurved ends, the members A, and B, then being adjusted scissor fashion to correspond with the width of the belt or ribbon to which the hooks 5 are secured so that the belt may be fastened to and between 50 the upper skirt supporting member A, and B. From this arrangement, it will be noticed that the main portion of the members A, and B, appear cross-wise upon the outside and over the belt x, as shown. 55

These skirt supporting members may be made of various sizes, and of any suitable material, and

Having thus described my said invention, what I claim as new and desire to secure by 60 United States Letters Patent is.

In a device of the character described the combination of two similar flat members preferably of sheet metal a pivot pin to pivotally unite said members crosswise, each 65 member having its ends bent so as to extend at right angles but in a parallel plane with the flat or body portion of each member, projecting ears secured to the ends of each member, and eyes adapted to be engaged by said 70 bent ends and ears as set forth.

In testimony whereof I affix my signature in presence of two witnesses.

ANNA CLEVES.
